UNITED STATES PATENT OFFICE.

LUCAS BARGER, OF NEW YORK, N. Y.

DESIGN FOR A GUN-SIGHT.

SPECIFICATION forming part of Design No. 34,244, dated March 19, 1901.

Application filed February 2, 1901. Serial No. 45,790. Term of patent 7 years.

To all whom it may concern:

Be it known that I, LUCAS BARGER, a citizen of the United States, residing in the city of New York, borough of Manhattan, in the county and State of New York, have invented and produced a certain new and original Design for Gun-Sights, of which the following is a specification, reference being had to the accompanying drawing, forming part thereof and showing a perspective view of the sight.

The leading feature of my design is shown in the accompanying facsimile.

The sight comprises a band or strip bent or otherwise formed to give it the contour shown. The upper portion A is a nearly complete circle and joins an outwardly-extending semicircular portion A' on each side.

These semicircular portions A' are of greater diameter than the upper portion A, as shown. The inwardly-extending ends of the semicircular portions approach nearly together and terminate in downwardly-extending ears A² 20 A², in each of which is a small hole a.

I claim—

The design for a gun-sight herein shown 25 and described.

In testimony that I claim the invention above set forth I affix my signature in presence of two witnesses.

LUCAS BARGER.

Witnesses:

CHARLES R. SEARLE,
IRVING I. RUSHWORTH.
